(No Model.)

J. H. FRYE & B. PITMAN.
LADDER.

No. 488,428.

Patented Dec. 20, 1892.

Attest,

C. M. Miles,

J. H. Frye,

B. Pitman,

By Woodford Atty.

UNITED STATES PATENT OFFICE.

JOHN H. FRYE AND BENN PITMAN, OF CINCINNATI, OHIO.

LADDER.

SPECIFICATION forming part of Letters Patent No. 488,428, dated December 20, 1892.

Application filed August 8, 1892. Serial No. 442,488. (No model.)

To all whom it may concern:

Be it known that we, JOHN H. FRYE and BENN PITMAN, citizens of the United States, residing at Cincinnati, in the county of Hamilton and State of Ohio, have invented certain new and useful Improvements in Ladders, of which the following is a specification.

Our invention relates to an improved ladder.

10 The object of our invention is to provide a strong ladder which can be used without danger for fire and other similar purposes where long ladders are required and safety is an essential requisite for the utility of the device.

15 The features of our invention are fully set forth in the description of the accompanying drawings making a part of this specification, in which—

Figure 1 is a plan view of our improvement 20 partly in section. Fig. 2 is a section on line x, x , Fig. 1. Fig. 3 is a section on line y, y , Fig. 2. Fig. 4 is a modification of Fig. 2. Fig. 5 is a view similar to Fig. 3, showing a modification. Fig. 6 is a sectional detail on 25 line v, v , Fig. 5.

1, 1, represent flattened metallic plates preferably of channel iron formed as shown in Fig. 2.

2 represents wooden stiles into which the 30 metallic plates or strips are preferably countersunk. These flat or flattened metallic plates are rigid throughout their length and are applied to the outer sides of the stiles, so that said plates constitute rigid braces and 35 are superior to simple wires laid along the length of the stiles of a ladder as heretofore.

3 represents wooden rungs mortised into the stiles 2.

4 represents bolts which at their end portions extend through bolt holes in the flat or flattened metallic plates and are secured by nuts as in Figs. 2 and 3, or by riveting as in Fig. 4. The bolts also extend through the stiles and through the rungs.

45 In Figs. 1 and 2 the metallic strips are shown of the channel iron form countersunk in the sides of the stile. In Fig. 4 these strips are shown as plain and countersunk simply for neatness; the countersinking is not essential. By this method of construction several 50 advantages are gained; first, the wooden stiles

and rungs are securely braced against collapsing, and are really a wooden lining to the metallic ladder, for the metallic strips and bolts form a skeleton ladder, so that if the 55 wood should rot or burn in any one section or rung, still the ladder is intact, or, if the wood be cracked, split, or if there be a defect in any portion, the metallic portion possesses sufficient strength to support the strain imposed upon it. The stiles of ladders and the rungs, are very easily broken when they are unsupported; the wood soon becomes impaired in strength, especially where they are tenoned into the stiles, and readily break. 60 But, by having a metallic ladder inclosed and braced by wooden stiles and rungs, a very strong and durable device is obtained, and the safety of the user is assured.

In the modification shown in Figs. 5 and 6, 70 the rung is supported by the metallic rod passing along the under side instead of through it, and the rungs are gained into the sides of the stiles.

Having described our invention what we 75 claim is—

1. A ladder, consisting of the stiles 2, the flat metallic plates 1 extending along the outer sides of the stiles and provided at intervals with bolt holes, the wooden rungs 3, and the 80 tie bolts 4 supporting the rungs and extending at their opposite end portions through the bolt holes in the flat metallic plates, substantially as described.

2. A ladder, consisting of the stiles 2, the flat metallic plates 1 extending along the outer sides of the stiles and provided at intervals with bolt holes, the wooden rungs 3, the tie bolts 4 supporting the rungs and extending at their opposite end portions through the 85 bolt holes in the flat metallic plates, and the nuts applied to the bolts for securing the latter and tightening the parts, substantially as described.

In testimony whereof we have hereunto set 90 our hands.

JOHN H. FRYE.
BENN PITMAN.

Witnesses:

T. SIMMONS,
C. W. MILES.
